UNITED STATES PATENT OFFICE.

HENRY C. BULL, OF NEW YORK, N. Y., ASSIGNOR TO HIMSELF AND M. A. SOUTHWORTH, OF NEW ORLEANS, LOUISIANA.

IMPROVEMENT IN TRUCKS FOR STREET-RAILWAY CARS.

Specification forming part of Letters Patent No. 159,070, dated January 26, 1875; application filed July 11, 1874.

To all whom it may concern:

Be it known that I, HENRY C. BULL, of New York, in the county of New York and State of New York, have invented a new and useful Improvement in the Construction of Street-Car Truck-Frames, of which the following is a specification:

The invention consists in connecting the sections of the tubular truck-frame by tubular joints, thus forming a continuous passage therein, as and for the purpose hereinafter described.

In the accompanying drawing, Figure 1 represents a plan view of a truck-frame constructed according to my invention. Fig. 2 is an edge view, showing the pedestal-blocks. Fig. 3 is an end elevation.

Similar letters of reference indicate corresponding parts.

A is the truck-frame; B B, the axles; C, the wheels. This frame A is made of tubing, the parts being connected together by means of screws and corner-pieces D, in the usual manner, having one or more longitudinal tubes, E, connected to the ends of the frame by the pieces F. G represents the pedestal-

blocks, which are rigidly attached to the sides of the frame by brazing, or by any other suitable means. H are lateral arms attached to the frame upon which the body of the car rests. I is a crank, made on one of the axles, by means of which power is applied for revolving the axle or propelling the car.

Thus constructed, the entire frame is adapted for use as a water-tank for supplying the boiler, and may be of any size found necessary or practicable.

The connections of feed and discharge pipes may be made in the usual or well-known manner.

I do not claim a vehicle-frame made of tubes or tubular sections; but

Having thus described my invention, what I claim as new, and desire to secure by Letters Patent, is—

The car-truck frame formed of tubular sections and tubular connecting corner-pieces D, combined as and for the purpose set forth.

HENRY C. BULL.
